JOHN FRED GATES, OF CORCORAN, CALIFORNIA.

PUMP CONTROL.

1,376,270.

Specification of Letters Patent. Patented Apr. 26, 1921.

Application filed February 13, 1918. Serial No. 216,897.

To all whom it may concern:

Be it known that I, JOHN FRED GATES, a citizen of the United States, residing at Corcoran, in the county of Kings and State 5 of California, have invented certain new and useful Improvements in Pump Controls, of which the following is a specification.

This invention is a pump control more 10 particularly adapted for the remote control by the flow of water from an outlet, wherein is made of a movable member that is more or less flexibly connected with a cut-out mechanism that coöperates with an 15 indicating device.

One object of the invention is to provide a control having its primary operating means so disposed that water or other fluid leaving an outlet will impinge against the 20 same.

Another object of the invention is to provide a cut-out mechanism that is adapted to be connected with the primary operative means, which cut-out mechanism includes 25 suitable devices and instrumentalities for automatically opening an electric circuit.

Still another object of the invention is to provide an indicating means that is simultaneously operated with the circuit opening 30 mechanism.

A further object of the invention is to provide the primary operative means with suitable devices to enable it to be operatively connected with an outlet such as a 35 pipe.

A still further object of the invention is to provide a cut-out mechanism that employs a hooked arm that is pivotally mounted and which serves as a trip member for 40 retaining and releasing a resilient element that is adapted to simultaneously close a circuit leading to an electric lamp, said resilient element operating an electric switch.

Broadly stated, the invention comprises 45 a primary operative means which is positioned at a remote point and includes a pivotally mounted gate that is flexibly connected with a hooked member that serves as a trip and release, said primary operative means being detachably secured in a pipe or other conduit so that the gate will be operated by fluid passing therethrough, said hooked arm being pivotally mounted within a casing so that one end thereof is 50 adapted to cooperate with an engaging member secured to the end of a resilient

member which has its other end secured to one wall of the receptacle, the other end of said arm, which is connected with the primary operative means, has connected to 60 it a spring whose other end may be adjustably connected with spaced hooks or other securing means, said spring being so formed that it is adapted to coöperate with a suitable circuit closing device, which device has connected to it a source of electric energy and an electric lamp, said engaging member being operatively connected with an electric switch, said switch being adapted to control the flow of electricity in a 70 connected circuit, and a block so arranged that when the engaging member engages with the hooked arm said block will act as a stop therefor.

One practical form of construction and assembly will be described and illustrated in the accompanying drawings, in which:

Figure 1 is a sectional view of the receptacle showing the several operative features contained therein, and a disconnected side 80 elevation of the end of a pipe having the primary operative means connected thereon, and

Fig. 2 is a sectional view of the primary operative means, on the line 2—2 of Fig. 1. 85

In the preferred embodiment about to be described a pipe 15 having a flange 16 is shown as the means for directing the flow of the water 17 against the pivotally mounted gate 18. The primary operative means is 90 mounted adjacent the end 16 of the pipe 15 by means of a short length of pipe 19, having the flanges 20 and 21. These flanges 20 and 21 are provided with alining holes through which are adapted to pass any suitable securing means, such as bolts.

The gate 18 is mounted on the shaft 22 and is held thereon by means of the screws 23. In order that the gate may be secured to the shaft, one end of the gate is provided 100 with a passage adapted to receive the shaft therein.

The shaft 22 is rotatably mounted in suitable bearings formed in the bosses 24 and 25. These bosses are preferably placed in 105 alinement with each other and offset relative to a diameter of the pipe 19. As shown in Fig. 2, the gate is approximately rectangular in shape, and when water is not passing, it lies transversely of the pipe. 110

To operate the gate 18 from outside the pipe 19, the shaft 22 has connected to it, a

lever 26. This lever 26 has an eye 27 formed at one end so that it may receive the shaft 22. As this lever 26 should be firmly secured to the shaft 22 a set screw 28 is employed. This set screw passes through a suitably threaded hole formed in the lever so that it may pass the eye 27 and engage with the shaft 22. The drawings show the lever 26 positioned at right angles to the shaft 22 to lie in a plane parallel to the gate 18. The other end of the lever 26 may also be provided with an eye 29 to permit connection with the flexible element 30.

The flexible element 30 extends from the eye 29 and over a pulley 31 that may depend from a suitable support indicated at 32. From this pulley 31 the element 30 passes through an opening 33 formed in the rear wall 34 of the casing or receptacle A. The element after passing through the opening 33 is adapted to pass over a suitably supported pulley 35. The end of the element 30 is adapted to be secured in the eye 36 formed in the end of the hooked arm generally indicated at 37. This arm is pivotally mounted at 38. As shown the arm is curved with varying degrees of curvature upon each side of the pivot 38.

The arm 37 is composed of two portions indicated at 39 and 40. The portion 40 is of such shape that it approximately forms one quarter of the circumference of a circle. The portion 40 may also serve as a trip. The free end of the portion 40 is preferably so shaped and formed that it is adapted to cooperate with an eye 41 formed in an engaging member 42.

The engaging member 42 is provided with two portions that extend oppositely from the eye 41. Each one of these portions is provided with a suitable hole adjacent its free end. The upper hole is adapted to have secured in it a flexible element 43. This element 43 is adapted to pass over a pulley 44 and have its other end suitably connected as at 45 with the handle 46 of an electric switch 47. The switch 47 is adapted to control the circuit indicated by the wires 48 and 49.

The lower hole of the other portion of the engaging member 42 is adapted to be engaged by the end 50 of a spiral spring 51. As shown the spring 51 has its lower end 52 connected with an eye 53 that may be suitably secured or screwed into the lower wall 54 of the casing A. To coöperate with the engaging member 42 there is provided a block 55 that may be secured to the wall of the receptacle in any suitable manner. As shown in Fig. 1 this block is horizontally placed with one end abutting against the rear wall 34. Its other end is so positioned that it will serve as a stop to prevent backward movement of the engaging member 42.

The spring 51 has at the point 56 its con-

65 the insertion of a switch arm 57 pivotally mounted at 58 to the block 59. As shown the block 59 is substantially L-shaped and may be secured to the back wall 34 in any suitable or customary manner. The switch 70 arm is adapted to engage with a contact 60 as shown in Fig. 1.

75 Connected with the contact 60 is a conductor 61 forming one side of a circuit leading to an electric lamp indicated at 62. The other terminal of the lamp has connected to it a conductor 63 forming the other part of the circuit. This conductor is connected at its other end with one terminal of a source 80 of electric energy indicated by the two dry cells 64. The other terminal of the battery 64 has connected to it a conductor 65 that has its other end connected with the block 59.

85 The eye 36 formed at the end of the arm 37 is adapted to be engaged with one end of a spring 66. The other end of this spring 66 is adapted to engage with any one of the hooks 67. These hooks may be mounted in a block 68 if so desired, and the block may be secured to the wall 69 of the casing A. 90 As shown the hooks 67 are preferably positioned at a point below the pivot 38 and upon the opposite wall so as to provide variations in tension or pull upon the arm 37.

95 The receptacle or casing A may be formed of suitable material and of such size and shape as will best adapt it to hold the various devices. As shown the casing is secured to a wall or other support B, by means of the brackets indicated at 70 and 71. These 100 brackets 70 and 71 may employ any usual attaching means such as is indicated by the rivets 72. In Fig. 1 it will be noted that the switch 47 is mounted upon the wall B. In order to provide for this positioning of the switch 47 exteriorly of the casing or receptacle A a hole or opening 73 is formed in the wall 69 of the receptacle to permit the connecting element 43 to pass therethrough.

105 When the arm 37 has its end 40 engaging with the eye 41 of the engaging member the spring 51 will ordinarily hold the arm in position. This will permit the closing of the switch 47 and take the slack out of the element 43. The spring 66 will be placed under 110 tension but not sufficiently to withdraw the curved end 40 from its engagement with the eye 41.

115 When the arm 37 is engaged with the eye 41 the element 30 will be in such a position that the water flowing will impinge upon the gate 18, moving it upward as shown to the right in Fig. 1. This will hold the arm 37 in position. As soon as the flow of water lessens until it finally ceases the gate 18 120 will drop to the vertical position which will permit the spring 66 to pull the end 40 from engagement with the eye 41.

125 The release of the engaging means 42 by the curved portion 40 will permit the spring 130

51 to retract which in doing so will pull on the element 43 opening the switch 47 thus breaking the circuit which includes the wires 48 and 49. At the same time the 5 spring 51 in retracting will cause the point of separation 56 to move downward carrying with it the switch arm 57.

As the arm 57 moves downward it breaks contact with the contact 60 and opens the 10 circuit that includes the battery 64 and the lamp 62. The lamp 62 will then be extinguished by the opening of the circuit.

Fig. 1 shows the primary operating means as being mounted in a short section of 15 flanged pipe 19 so that the means may be inserted in the outlet pipe at a suitable point. If desired, the length of pipe shown at the right may be disconnected and the water will then flow freely from the flanged end 20 21 into a convenient receptacle.

What is claimed is:

1. A circuit controlling device including 25 separate switch arms, an elastic coupling element adapted to be connected to the switch arms and to be tensionably stretched upon the setting of the arms in a predetermined position, means for holding under given conditions, the coupler element as stretched between the switch arms and 30 means for releasing the coupler element in an emergency whereby it relaxes and shifts the switches to another predetermined position.

2. A circuit controlling device including a 35 trip, a trip engaged member, means for re-

taining the trip and member in mutual engagement under given conditions, adjustable means for tensioning the trip to disengage it from the member upon failure of the retaining means, switch arms for separate 40 circuits, tensionable means coupling the engaged member to a switch arm of one circuit and flexible means coupling the member to a switch arm of another circuit, said tensionable coupling means being tensioned to 45 move and draw the engaged member, upon disengagement of the trip from the latter, for shifting both switch arms to a predetermined position.

3. A circuit controlling device including a 50 trip, a trip engaged member, means for retaining the said trip in engagement with the engaged member under certain conditions, said trip being tensioned to disengage the member upon failure of the retaining 55 means, means for connecting the member with the operating arm of an electric switch, and a tensionable element connected at one end to the said member and at its other to the arm of another switch, said element being tensioned to shift the engaged member, when released from the trip, for operating the switches.

In testimony whereof I affix my signature in presence of two witnesses.

JOHN FRED GATES.
